THOMAS S. HUDSON, OF EAST CAMBRIDGE, MASSACHUSETTS.

Design No. 3,342, dated January 19, 1869.

DESIGN FOR AN INKSTAND.

The Schedule referred to in these Letters Patent and making part of the same.

To all whom it may concern:

Be it known that I, THOMAS S. HUDSON, of East Cambridge, in the county of Middlesex, and State of Massachusetts, have originated a new Design for a Combined Inkstand and Sponge-Cup, of which the following is a full, clear, and exact description, reference being had to the accompanying drawings, making part of this specification, in which—

In the drawings—

A represents the inkstand, from one side of which projects the dipping-cup b.

On the top of the inkstand A is a cup or receptacle, B, for containing sponge saturated with water.

What I claim as my invention, and desire to secure by Letters Patent, is—

The design for a combined inkstand and sponge-cup, herein shown and described.

Witnesses: THOS. S. HUDSON.
